UNITED STATES PATENT OFFICE.

ENRICO RE, OF CAMDEN, NEW JERSEY.

KEYBOARD FOR GUITARS OR SIMILAR INSTRUMENTS.

1,207,213.

Specification of Letters Patent.

Patented Dec. 5, 1916.

Application filed April 12, 1916. Serial No. 90,684.

To all whom it may concern:

Be it known that I, ENRICO RE, a subject of the King of Italy, residing at Camden, in the county of Camden and State of New Jersey, have invented certain new and useful Improvements in Keyboards for Guitars or Similar Instruments, of which the following is a specification, reference being had to the accompanying drawings.

10 This invention relates to certain improvements in keyboards for guitars or similar instruments and it is an object of the invention to provide a novel and improved keyboard which may be readily and conveniently applied to the neck or finger board of the instrument.

Furthermore it is an object of the invention to provide a novel and improved device of this general character including a 20 plurality of buttons having coacting therewith means for normally maintaining the same out of contact with the strings of an instrument when the board is in applied position.

25 The invention consists in the details of construction and in the combination and arrangement of the several parts of my improved keyboard whereby certain important advantages are attained and the device is 30 rendered simpler, less expensive and otherwise more convenient and advantageous for use, all as will be hereinafter more fully set forth.

The novel features of the invention will 35 hereinafter be definitely claimed.

In order that my invention may be the better understood, I will now proceed to describe the same with reference to the accompanying drawings, wherein—

40 Figure 1 is a view in top plan illustrating a keyboard constructed in accordance with an embodiment of my invention in applied position; Fig. 2 is an enlarged fragmentary view in top plan of my improved keyboard as herein embodied; Fig. 3 is an enlarged fragmentary view in bottom plan of my improved keyboard as herein disclosed; Fig. 4 is an enlarged fragmentary sectional view of my improved keyboard, the coacting portion of the neck being shown in elevation; Fig. 5 is an enlarged transverse sectional view taken through my improved keyboard and the coacting portion of the neck, the buttons being shown in elevation.

45 50 55 60 65 70 75 80 85 90 95 100 105 110

As disclosed in the accompanying draw-

ings, N denotes the neck of a string musical instrument provided with the finger-board B having frets F, and 1 denotes an elongated plate adapted to overlie the finger-board B and of substantially the same configuration in plan. The opposite extremities of the plate 1 are provided with the spring arms 2 adapted to embrace the neck N and frictionally engage the same in order to maintain the plate 1 in applied position.

The under surface of the plate 1 is provided with the depending blocks 3 having their under faces grooved, as at 4, so that said blocks 3 may straddle the frets F and also serve to maintain the plate 1 in predetermined spaced relation relative to the finger-board B so that no obstruction will be offered to the vibration of the strings S.

The plate 1 is provided with a plurality 75 of series of longitudinally spaced openings 5, each of said series coacting with a single string S and disposed between the frets F when the plate 1 is in applied position. Loosely directed through each of the openings 5 is a button 6 having its opposite extremities provided with the heads 7 and 7' whereby the button 6 is held maintained against removal from the plate 1, and the intermediate portion of the button 6 is of such a length as to permit sufficient depression of the button to properly engage a string S positioned therebeneath.

Each of the buttons 6 as herein embodied, is normally maintained in elevated or raised position relative to its coacting string through the medium of the springs 8 herein disclosed as coil springs having their inner extremities extended within the recesses 9 produced at diametrically opposed points in the intermediate portions of the button 6 and with their opposite or outer extremities seated within the recesses or depressions 10 suitably produced in the walls of the depressions or recesses 10. The button 6 is suspended by the springs 8 so that the button may be readily and conveniently depressed to engage a string and the button 6 will be raised or elevated as soon as the pressure of a finger is removed therefrom. It is also to be noted that the outer faces of the buttons 6 are provided with the symbols 11 whereby a desired pitch or tone may be obtained. As herein disclosed, the symbols 11 are of the same character as the singing notes.

From the foregoing description, it is

thought to be obvious that a keyboard constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

1. A keyboard attachment for string instruments including an elongated plate provided with means whereby it may be detachably applied in operative position and having a plurality of openings, a button freely movable within each of the openings, said button being provided with substantially diametrically opposed recesses, and coil springs seated within said recesses and coacting with the wall of the opening for normally maintaining the button in a raised position.

Copies of this patent may be obtained for five cents each, by addressing the "Commissioner of Patents, Washington, D. C."

2. A keyboard attachment for string instruments including an elongated plate provided with means whereby it may be detachably applied in operative position and having a plurality of openings, a button freely movable within each of the openings, said button being provided with substantially diametrically opposed recesses, and coil springs seated within said recesses and coacting with the wall of the opening for normally maintaining the button in a raised position, the walls of the openings being provided with recesses in which the outer extremities of the springs are seated.

3. In combination with a finger-board of a string instrument provided with frets, a keyboard adapted to overlie the finger-board, blocks depending from the keyboard and having their under surfaces grooved so that said blocks may straddle the frets, and movable buttons carried by and disposed through the keyboard.

In testimony whereof I hereunto affix my signature in the presence of two witnesses.

ENRICO RE.
